VACUUM NOZZLE FOR CLEANING BUCKET SEATS AND CARS

William M. Hoadley, Box 5,
Otis Orchards, Wash. 99027

Filed Sept. 19, 1968, Ser. No. 13,618

Term of patent 14 years

Int. Cl. D15—07

U.S. Cl. D49—18

FIG. 1 is a top plan view of the vacuum nozzle embodying the instant design;

FIG. 2 is a side view of the vacuum nozzle reversed in position; and

FIG. 3 is a bottom plan view of the vacuum nozzle turned 90 degrees.

The undisclosed side of the vacuum nozzle is a mirror image of the view shown in FIG. 2.

I claim:

The ornamental design for a vacuum nozzle for cleaning bucket seats and cars, as shown and described.
